UNITED STATES PATENT OFFICE.

GEORGE W. CHRISTOPH, OF WAREHOUSE POINT, CONNECTICUT.

SAND-BLASTING APPARATUS.

Application filed October 27, 1921. Serial No. 510,932.

To all whom it may concern:

Be it known that I, GEORGE W. CHRISTOPH, citizen of the United States, residing at Warehouse Point, in the county of Hartford and State of Connecticut, have invented new and useful Improvements in Sand-Blasting Apparatus, of which the following is a specification.

The present invention relates to sand blasting apparatus and, while capable of general application, it is more particularly useful in connection with sand blasting devices of the general type in which relatively small articles are supported within a work chamber and are there subjected to a blast of sand while they are being manipulated by an attendant.

In apparatus of the type above referred to, it is customary to cause the sand, which has been injected into the work chamber and has performed its function upon the work, to be returned into a supply hopper from which it was originally drawn, in order that the same mass of sand may be used over and over again to continue the sand blasting operations, the sand being continuously withdrawn from the hopper and supplied to a sand blast nozzle within the work chamber and being continuously returned from the work chamber to the hopper as the sand blasting operation progresses.

In the use of such apparatus, fine particles of dust are continually becoming disintegrated from the grains of sand as the latter pass through the sand blast nozzle and are whirled about within the work chamber. More or less dust and dirt is also produced by the abrasive action of the sand upon the surface of the articles being operated upon. Consequently the proportional amount of dust and dirt which is intermixed with the sand increases gradually during the continued use of the apparatus, as heretofore constructed, and the effectiveness of the sand as an abrasive element becomes correspondingly diminished, because only clean, sharp sand is effective for the sand blasting operation.

One of the objects of the present invention is to provide improved means for separating dust and dirt from the sand after it has acted upon the articles within the work chamber so that the sand, when returned to the supply hopper, will be free from dust

and may be repeatedly injected into the work chamber without acting any less effectively upon the work.

Another object of the invention is to provide, in connection with a transparent wall section or window in the work chamber of a sand blasting device such as above described, means for keeping said transparent wall section free from dust and dirt throughout the progress of the sand blasting operation, so that the latter may be clearly and continuously visible from the exterior of the chamber.

Sand blasting devices of the general character indicated have heretofore been provided with a ventilating pipe, the pipe opening into the sand blast chamber and being effective to remove a certain amount of dust therefrom.

Another object of this invention is to accomplish the objects already set forth by the use of the usual ventilating pipe.

With these and other objects in view, as may hereinafter appear, the invention consists in the features of construction and combinations and arrangements of parts hereinafter described and particularly pointed out in the appended claims.

The invention will be disclosed with the aid of the accompanying drawings illustrating what is now considered to be the preferred embodiment thereof.

In the drawings,

Fig. 1 is a side elevational view of the apparatus; and

Fig. 2 is a view partially in side elevation and partially in vertical section thereof.

Referring to the drawings, the invention has been illustrated as embodied in a sand blasting apparatus of a type well known in the art. In general, this apparatus comprises a work chamber 5, in which the sand blasting operation takes place; a sand hopper 6 for supplying the sand used in the blasting operation, said hopper being located directly beneath the work chamber and connected therewith so that the sand may be returned from the work chamber into the hopper after it has acted upon the work; a horizontal work support 7, extending transversely across the work chamber; a downwardly directed sand blast nozzle 8 located within the work chamber and above the work support; and a feed pipe 9, con-

necting the bottom of the sand hopper 6 with the nozzle 8 for delivering sand to the latter.

In the construction shown, the work chamber 5 is of rectangular cross-sectional shape, having four vertically disposed side walls 10 enclosing the central portion of the chamber, and corresponding inwardly sloping side walls 11 and 12 extending respectively 5 above and below the walls 10. There are four sloping side walls 11, connecting the walls 10 with a rectangular horizontal top wall 13. Two of the sloping side walls 12, as shown in Fig. 2, extend downwardly 10 from the lower edges of the corresponding walls 10 at opposite sides of the apparatus. The two walls 12 just referred to, are connected at the front and rear of the apparatus by the two other side walls 12 (Fig. 15) the upper portions which slope inwardly while the lower portions thereof are substantially vertical, as indicated at 12'. The four side walls 12 do not meet at their lower edges and by reason of the above described 20 vertical portions 12' of the front and rear side walls 12, an elongated opening 35 is provided at the bottom of the work chamber, this opening extending horizontally and leading into a short vertical neck or conduit 30 14, of horizontally elongated rectangular cross-section, which connects the work chamber 5 with the hopper 6.

The lower portion of the hopper 6 is substantially of the shape of an inverted rectangular pyramid having its lower extremity connected through a suitable manually-operated sand valve 15 with the feed pipe 9. The upper portion of the sand hopper 6 comprises two side walls 16 which 35 slope upwardly from opposite side walls of the lower portion of the hopper, and two vertical walls 16' which connect the walls 16. A filling opening is located in one of the upper walls of the hopper 6 and a suitable closure 17 is provided for said opening. The work chamber 5 and the hopper 6 are rigidly supported by a suitable 40 frame 18.

The work support 7 consists of a rectangular tray having a screen-like bottom for supporting the articles to be operated upon, the mesh of the screen being sufficiently coarse to permit the free passage therethrough of the sand. The frame of 45 the work support rests upon a pair of horizontal angle iron bars 20, which extend rigidly across the work chamber and are rigidly secured to the walls thereof.

The sand blast nozzle 8 depends from a 50 casting 21 which is supported near the top of the work chamber. The upper end of the feed pipe 9 extends through the sloping side walls at the top of the work chamber and through the side of the casting 55 21, the feed pipe opening into a chamber

22 within said casting. The sand is drawn through the feed pipe 9 in the usual manner, by means of the injector effect of a current of compressed air which is directed into the chamber 22 through an air conduit 70 23, entering the work chamber at the top thereof and connected with a suitable compressed air reservoir (not shown).

A partial vacuum is thus created in chamber 22 to cause a current of air to flow into the feed pipe inlet 9' and upward therethrough to carry sand fed in regulated quantities from the sand valve 15 into chamber 22.

At the front of the work chamber the side wall 10 thereof is provided with two hand holes 25 through which an attendant may insert his hands to manipulate the articles upon the work rest while they are being subjected to the action of the sand blast. The hand holes 25 are surrounded by annular flanges 26 which are turned inwardly from the work chamber wall and flexible cuffs 27 are fitted over said flanges, as shown in Fig. 2. In accordance with 80 the usual practice, the inner extremities of the cuffs 27 are gathered by means of an elastic cord 27' or the like so that the cuffs will fit tightly around the wrists of the attendant to prevent escape of sand through 85 the hand holes. Suitably hinged doors 28 are arranged at opposite sides of the side walls 10 of the work chamber to permit the insertion and removal of the work supporting trays, the latter sliding upon the 90 angle iron bars 20. The upper side walls 11 of the work chamber are provided with transparent portions 30 constituting windows which render visible the action of the sand blast upon the work.

The construction so far described is substantially the same as that of a well known type of sand blasting apparatus which has been in general use heretofore. The features of the present invention have been 100 shown as embodied in the specific apparatus above described merely by way of 105 illustrative example and it is recognized that the invention is capable of use in connection with sand blasting devices differing in many particulars of construction from that described and shown in the drawings.

As already explained, the use of such apparatus results in the formation of dust and dirt which becomes intermixed with the sand as it is repeatedly used in the work chamber. The present invention, however, contemplates the removal of these particles of dust and dirt from the sand after the sand has acted upon the work and before it is returned into the hopper 6. In carrying out this feature of the invention, provision is made for gathering together the flying particles of sand and dust and causing them to fall through the lower portion of the work 115 120 125 130 135

chamber, adjacent the mouth of the neck 14, in a thin sheet-like stream, and for causing a constant flow of air through the thin stream of sand so that the particles of dust 5 and dirt therein which are lighter than the grains of sand, will be separated from the sand and carried away with the air.

To the accomplishment of the above result, the work chamber is provided with a 10 false bottom comprising three plates or partitions 32, 33 and 33'. The plate 32 is spaced a short distance above the side wall 12 at the side of the exhaust conduit 36. The plates 33 and 33' are arranged with their 15 ends slightly overlapping each other and together these plates form a partition which is spaced a short distance above the opposite side wall 12. The overlapping ends of the partition plates 33 and 33' are spaced apart 20 to provide an air or ventilating passage 45 the function of which will be hereinafter described. The two plates 32 and 33 terminate at their lower extremities in straight 25 horizontal edges which are disposed in spaced-apart relation in substantially the same vertical plane, the latter extending axially through the work chamber 5 and the hopper 6. As the sand reaches the lower portion of the work chamber, the downwardly converging partitions 32, 33 and 33' 30 serve as deflectors to divert the sand toward the vertical plane of the outlet port 35. The velocity of the sand is thereby arrested and it is caused to flow in a thin stream over the 35 lower edge of the plate or partition 33 which directs it centrally through the neck 14 and into the hopper 6.

In order that a current of air may be forced through the stream of sand and dust 40 issuing from the outlet port 35, the air passage 34, is connected, at the rear of the apparatus, with a ventilating or exhaust conduit 36 leading to a blower or fan 36' by means of which air may be drawn through 45 the passage 34. At the front of the apparatus, the air passage 34 is connected through passage 45, with the interior of the work chamber. Air is admitted to the work 50 chamber through an air inlet 39 in the top wall 13 thereof. When the fan connected with the exhaust conduit 36 is operating, air is drawn through the inlet 39, through the work chamber, the ventilating passage 45 and the air passage 34, into the exhaust conduit 36, the air passing through the thin 55 stream of sand issuing from the outlet port 35 between the partition plates 32 and 33. The lighter particles, such as the dust and dirt, contained in the sand are separated 60 therefrom by the action of the current of air and are drawn into the exhaust conduit 36, and thus only clean sand is permitted to enter the hopper 6. By arranging the lower edges of the plates 32 and 33 at different 65 elevations, bearing the relation shown to

the mouth of the exhaust conduit 36, there is no liability of any of the heavier grains of sand being drawn into the exhaust conduit if the force of the air current is properly regulated. A damper 44 may be provided by which the force of the current of air may be regulated at will for the purpose of rendering its action most efficient for the removal of the dust. Preferably this damper 44 is located as shown at the junction of the exhaust conduit 36 and the air passage 34. It will be noticed also that the partition plate 33' overlaps the inner face of the partition plate 33, this arrangement insuring against the escape of sand through the ventilating passage 45. The draft produced in the ventilating passage 45 by the current of air moving through the passage 34, effects the elimination from the work chamber of a certain amount of the dust and dirt contained in the sand before the latter reaches the outlet port 35.

In sand blasting devices of this general type heretofore used, difficulty has been experienced by the attendant in watching the progress of the blasting operation by reason of the fact that the transparent portions or windows 30 of the work chamber quickly became covered with a layer of dust from sand blasting operation which obscured the 90 vision.

In the present construction, the air which is drawn in through the inlet 39 is diverted by means of a deflector 40 across the inside surfaces of the windows 30 and serves to 100 keep these windows free from dust, during the sand blasting operation.

While the particulars of construction herein set forth are well suited to the illustrated embodiment of the invention, these 105 particulars are not essential since they may be variously modified without departing from the true scope of the invention as defined by the following claims.

What is claimed is:

1. In a sand blasting apparatus, the combination of a work chamber in which the sand blasting operation takes place, said chamber having an outlet at the bottom thereof through which the sand flows by 115 gravity in a thin stream, a work support in said chamber above said outlet, a nozzle for directing a blast of sand against the work in said chamber, an air jacket surrounding the lower walls of the work chamber, said 120 lower walls being provided with an air passage connecting said jacket with the work chamber, said passage inclining downwardly from said jacket to said chamber to insure against the passage of sand therethrough, a hopper beneath said jacket for receiving the sand after it has operated upon the work, and passed through said outlet and air jacket, and means for drawing air from the work chamber through said 125 130

passage and causing it to pass through the sand stream in said jacket to effect the removal of dust and dirt from the sand.

2. In a sand blasting apparatus, the combination of a work chamber in which the sand blasting operation takes place, a work support in said chamber, a nozzle for directing a blast of sand against the work in said chamber, a transparent portion in the wall 10 of said chamber through which the progress of the sand blasting operation may be watched, and means for preventing dust and dirt from accumulating upon the inner face of said transparent portion so as to obscure 15 the view of the interior.

3. In a sand blasting apparatus, the combination of a work chamber in which the sand blasting operation takes place, a work support in said chamber, a nozzle for directing a blast of sand against the work in said chamber, a transparent portion in the wall of said chamber through which the progress of the sand blasting operation may be watched, and means for directing a draft 20 of air across the inner face of said transparent portion to keep it clear of dust resulting from the blasting operation.

4. In a sand blasting apparatus, the combination of a work chamber within which 30 the sand blasting operation takes place said chamber having a sand outlet through which the sand may escape after it has acted upon the work, a work support within the work chamber, a nozzle for directing a blast 35 of sand against the work, a hopper for receiving the sand which flows through said outlet, a conduit connecting said hopper with said nozzle, a transparent portion in the wall of the work chamber to render the 40 interior of said chamber visible, and means for producing an air draft and directing it across the inner surface of said transparent portion to keep same free from dust and dirt during the continuance of the sand 45 blasting operation and for causing the air draft to pass through the sand flowing through said outlet to remove dust and dirt therefrom.

5. In a sand blasting apparatus, the combination, of a work chamber having an air 50 inlet at the top and a horizontally elongated sand outlet at the bottom thereof and side walls sloping upwardly from said outlet at opposite sides of the work chamber, a sand 55 blast nozzle within the work chamber, a work support beneath said nozzle, a hopper beneath the work chamber and connected with said outlet, a conduit connecting said hopper and said nozzle, downwardly sloping par-

titions spaced from the inner faces of said 60 sloping side walls, to provide an air jacket between said partitions and chamber walls and to intercept falling particles of sand and deflect them toward the lower edges of said partitions, said lower edges being 65 spaced from each other in a substantially vertical plane to provide a horizontally elongated outlet port through which the sand may flow in a thin stream across said air jacket, through said sand outlet and into said 70 hopper, and one of said partitions comprising two sections having spaced apart overlapping ends arranged to provide a passage extending to said air jacket, means for drawing air through said air passage and 75 air jacket and through said stream of sand to remove dust and dirt from the latter.

6. In a sand blasting apparatus, the combination, of a work chamber having an air inlet at the top and a horizontally elongated 80 sand outlet at the bottom thereof and side walls sloping upwardly from said outlet at opposite sides of the work chamber, a sand blast nozzle within the work chamber, a work support beneath said nozzle, a hopper beneath 85 the work chamber and connected with said outlet, a conduit connecting said hopper and said nozzle, downwardly sloping partitions spaced from the inner faces of said 90 sloping side walls, to provide an air jacket between said partitions and chamber walls and to intercept falling particles of sand and deflect them toward the lower edges of said partitions, said lower edges being spaced 95 from each other in a substantially vertical plane to provide a horizontally elongated outlet port through which the sand may flow in a thin stream across said air jacket, through said sand outlet, and into said 100 hopper, and one of said partitions comprising two sections having spaced apart overlapping ends arranged to provide a passage 105 extending to said air jacket, an air exhausting device connected to said air jacket at one side of said work chamber for drawing air through said air passage and air jacket and through said sand stream to remove dust and dirt from the sand, and an extension of the downwardly sloping partition at the side of the work chamber to which the exhausting device is connected for preventing the production by means of said device of a draft of air through said outlet port.

In testimony whereof I have affixed my 115 signature.

GEORGE W. CHRISTOPH.
